(57) CLAIM

The ornamental design for a bottle, as shown and described.

DESCRIPTION

FIG. 1 is a front perspective view of a bottle showing my new design;

FIG. 2 is a front view of the bottle shown in FIG. 1;

FIG. 3 is a rear view of the bottle shown in FIG. 1;

FIG. 4 is a right side view of the bottle shown in FIG. 1;

FIG. 5 is a left side view of the bottle shown in FIG. 1;

FIG. 6 is a top view of the bottle shown in FIG. 1; and,

FIG. 7 is a bottom view of the bottle shown in FIG. 1.

The broken line showing of the wording on the bottle bottom and portions of the bottom surface of the bottle shows unclaimed subject matter for the design in those drawings.
